HOLDER FOR SIGN CARDS OR THE LIKE

George J. Smith, 8606 Flower Ave., Takoma Park, Md.

Filed Sept. 8, 1961, Ser. No. 66,655

Term of patent 14 years

(Cl. D1—3)

FIG. 1 is a top view of a combined toothpaste discards or the like embodying my new design;

FIG. 2 is a side elevational view thereof;

FIG. 3 is a front elevational view thereof;

FIG. 4 is a rear elevational view thereof; and

FIG. 5 is a cross-sectional view thereof, taken on the line 5—5 of FIG. 3.

The broken-line representation of a price tag moulding in FIG. 2 is for purposes of illustration only.

I claim:

The ornamental design for holder for sign cards or the like, as shown and described.
